COMBINATION GAS ENGINE MUFFLER AND INSECTICIDE SPRAYER

Arthur C. Cragg, St. Paul, Minn., assignor to Donaldson Company, Inc., St. Paul, Minn., a corporation of Delaware

Application March 1, 1956, Serial No. 40,419

Term of patent 14 years

(Cl. D31—3)

Fig. 1 is a view in perspective of a combination gas engine muffler and insecticide sprayer showing my new design with a supply container shown in dotted lines for purpose of illustration only; and

Fig. 2 is a view in side elevation showing the side opposite that shown in Fig. 1.

I claim:

The ornamental design for a combination gas engine muffler and insecticide sprayer, as shown and described.
